(57) **CLAIM**

The ornamental design for a hybrid cell phone protector case, as shown and described.

DESCRIPTION

FIG. 1 is a front perspective view of the hybrid cell phone protector case, in which all three components (the inner soft portion, hard portion, and holster) are shown together in an assembled state;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top view thereof;

FIG. 8 is a bottom view thereof;

FIG. 9 is a front perspective view of the hybrid cell phone protector case, showing only the inner soft portion for clarity of disclosure;

FIG. 10 is a rear perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top view thereof;

FIG. 16 is a bottom view thereof;

FIG. 17 is a front perspective view of the hybrid cell phone protector case, showing only the hard portion for clarity of disclosure;

FIG. 18 is a rear perspective view thereof.

FIG. 19 is another rear perspective view thereof with the stand in an open position;

FIG. 20 is a front elevational view thereof;

FIG. 21 is a rear elevational view thereof;

FIG. 22 is a right side view thereof;

FIG. 23 is a rear side view thereof;

FIG. 24 is a top view thereof;

FIG. 25 is a bottom view thereof;

FIG. 26 is a front perspective view of the hybrid cell phone protector case, showing only the holster for clarity of disclosure;

FIG. 27 is a rear perspective view thereof;

FIG. 28 is a front elevational view thereof;

FIG. 29 is a rear elevational view thereof;

FIG. 30 is a right side elevational view thereof;

FIG. 31 is a left side elevational view thereof;

FIG. 32 is a top view thereof;

FIG. 33 is a bottom view thereof;

FIG. 34 is a front perspective view of the hybrid cell phone protector case, in which two of the components (the inner soft portion and the hard portion) are shown together in an assembled state with the stand in an open position;

FIG. 35 is a rear perspective view thereof with the stand in an open position;

FIG. 36 is a front elevational view thereof;

FIG. 37 is a rear elevational view thereof;

FIG. 38 is a right side elevational view thereof;

FIG. 39 is a left side elevational view thereof;

FIG. 40 is a top view thereof;

FIG. 41 is a bottom view thereof;

FIG. 42 is a front and side perspective view of the hybrid cell phone protector case in which all three components (the inner

soft portion, hard portion, and holster) are shown together in an assembled state and with the holster clip in a fully open position;

FIG. 43 is a rear and side perspective view of the hybrid cell phone protector case in which all three components (the inner soft portion, hard portion, and holster) are shown together in an assembled state and with the holster clip in a full open position;

FIG. 44 is a front elevational view thereof;

FIG. 45 is a rear elevational view thereof;

FIG. 46 is a right side elevational view thereof;

FIG. 47 is a left side elevational view thereof;

FIG. 48 is a top view thereof;

FIG. 49 is a bottom view thereof;

FIG. 50 is a front perspective view of the hybrid cell phone protector case in which all three components (the inner soft portion, hard portion, and holster) are shown together in an assembled state with the holster rotated 90 degrees and in a fully open position;

FIG. 51 is a front elevational view thereof;

FIG. 52 is a rear elevational view thereof;

FIG. 53 is a right side elevational view thereof;

FIG. 54 is a left side elevational view thereof;

FIG. 55 is a top view thereof; and,

FIG. 56 is a bottom view thereof.
